UNITED STATES PATENT OFFICE.

CHESTER MILO POETSCH, OF CHICAGO, ILLINOIS.

RADIATOR-COVER.

1,224,501.

Specification of Letters Patent.

Patented May 1, 1917.

Application filed December 11, 1915. Serial No. 66,270.

To all whom it may concern:

Be it known that I, CHESTER MILO POETSCH, a citizen of the United States, residing at Chicago, in the county of Cook and State of Illinois, have invented a new and useful Radiator-Cover, of which the following is the specification.

The object of my invention is to provide a covering for the top, sides and back of radiators of all sizes and kinds, of simple, durable and economical construction and which will add to the appearance of the radiator and conform to the woodwork and furnishings of the room.

15 A further object of my invention is to provide a device for use in connection with steam or other radiators which will serve not only as a cover for the radiator but will also serve to contain a supply of water 20 for slow vaporizing in order to render the atmosphere of the room in which the radiator is placed humid.

25 A further object of my invention is to provide a device for use in connection with radiators which may be used as a window seat, shelf, ledge or the like.

30 The special and novel phases of my invention herein disclosed will be better understood by reference to the following detailed description which is to be taken in conjunction with the accompanying drawings, wherein—

35 Figure 1 is a front elevation of a device embodying my invention in place upon a radiator showing a portion of the top or shelf portion broken away.

Fig. 2 is an end elevation thereof.

Fig. 3 is a transverse vertical section on the line 3—3 of Fig. 1.

40 In carrying out my invention, I have special regard for economy of construction, and the various parts which enter into the construction of my device may be produced with little, if any, special machinery as will 45 appear from the further description.

45 In carrying out my invention, I first provide the end members 10 of any desirable ornamentation preferably such as will conform to the radiator in size, shape, design 50 and color of finish. To these end members 10, I secure a back member 11 preferably of sheet metal which may be secured to flanges 12 on the end members 10 by any suitable means such as bolts 13. I next provide a 55 support 14 for the top which may be of ordinary angle iron and which serves the

further purpose of spacing the two end members 10 apart and holding them in fixed position relative to each other.

In order that the device as a whole may 60 be kept in rigid relation to the radiator, I next provide fastening means 15, one end 16 of which is secured to the member 14, the other end being brought down and around a portion of the radiator as shown 65 in Fig. 3, and either secured at the other end to the member 14 or by means of the screw bolt 17 which latter method will permit of adjustment. These fastening means may be distributed throughout the length of the 70 radiator in such numbers as may be required to firmly hold the device as a whole in contact with the radiator so as to prevent slipping about and rattling. In the practice in the past, it has been customary to 75 provide the necessary and desirable moisture in the room by means of open receptacles sitting about the room or exposed receptacles in or about the radiator. I have provided means for supplying moisture in 80 order to render the heated air of the room humid, out of sight and unexposed to the collection of dust and out of danger of being upset or the water spilled.

I provide a water trough 18 having a 85 flange 19 at the top and back thereof which fits down over and rests on the back member 11. This trough is shaped so that it fits down in between the back or sections of the radiator and the back member 11 of 90 my radiator cover. This trough may be the full length of the radiator or any desired length.

I next provide a top 20 for my complete device which should be preferably of metal 95 of sufficient strength to enable it to fulfil the function of a seat or shelf. This top member 20 contains a grooved track member 21 which registers with the supporting member 14, the purpose being to keep the 100 top member 20 in alignment when it is moved backward and forward for the purpose of permitting the water trough 18 to be filled, examined or removed. The ends 22 of the top member 20 fit into and against 105 the top of the end members 10 so that the top surface is entirely smooth. At the front and back, the top member is flanged downwardly as at 23 both for the purpose of holding it rigidly in place, preventing any 110 sidewise movement (endwise movement being prevented by engagement with the

flanged upper portion of the end members 10), and for the further purpose of producing the desired deflector action on the heated and moisture-laden air which comes 5 from the radiator and which is thereby directed first downwardly and then following the law of heated air, rising to the top of the room thereby aiding in warming the floors, whereas without my device, the 10 heated air rises to the ceiling and the floors remain unwarmed.

It will be seen from my description that I have provided a combined radiator cover and deflector and window seat or shelf 15 with the added feature of supplying moisture for vaporizing and not only preserving all the ornamental features of the usual radiator but adding thereto. My device is also such a one as can be made and carried 20 in stock for any and all types and kinds of radiators and does not need to be built specially for the particular radiator as is the case with so many of the devices of this 25 nature heretofore offered on the market.

While I have herein disclosed one embodiment of the present invention, it is apparent and I am aware that changes in detail may

be made in materials, design and size without deviating from the spirit of my invention, and I desire that the protection herein 30 sought should include such changes and modifications in detail as reasonably may be made with the terms of the appended claim.

Having fully described my invention, 35 what I claim and desire to secure by Letters Patent is:—

A device of the class described comprising sides, a back, means for detachably securing the sides to the back, a removable, 40 adjustable shelf top, means for detachably and slidably connecting the top with the back and sides, a moisture reservoir supported by the back, means engaging with the radiator and slidably engaged with the 45 top for attaching the top and associated parts to and supporting on the radiator.

In witness whereof, I hereunto subscribe my name to this specification in the presence of two witnesses.

CHESTER MILO POETSCH.
